INCENDIARY BOMB SCOOP

Thoger G. Jungeren, Summit, N. J.

Application July 15, 1942, Serial No. 451,036

5 Claims. (Cl. 294—55)

This invention relates to an incendiary bomb scoop and more particularly to a manually operated heat insulated scoop provided with a hinged cover, adapted to be operated and controlled manually, and a long handle.

It is well known that incendiary bombs are capable of developing intense heat of a nature which would destroy ordinary materials. It has been suggested that these incendiary bombs be controlled by treatment with a fine spray of water. However, such treatment is not entirely satisfactory because some time elapses before the bomb can be placed under control and during this elapsed time considerable damage may have been effected. Attempts to dislocate a bomb from a vulnerable spot with ordinary means will result in the destruction of such means unless the same is capable of withstanding very high temperatures such as is developed by an incendiary bomb.

It is an object of the instant invention to provide an incendiary bomb dislocating means of an insulated scoop-like construction capable of actually picking up an incendiary bomb so that it may be carried to a relatively safe place.

It is a further object of the instant invention to provide an incendiary bomb handling means capable of maintaining and holding an incendiary bomb until it becomes dissipated.

Other objects and the nature and advantages of the invention will be apparent from the following description taken in conjunction with the accompanying drawing, wherein:

Figure 1 is a view in perspective of an incendiary bomb in accordance with the invention with a portion of the cover of the scoop part broken away in order to disclose a portion of the interior thereof. An incendiary bomb is shown close to the scoop.

Figure 2 is a view similar to Fig. 1 with the cover of the scoop in open position.

Figure 3 is a vertical sectional view of the scoop and a portion of the handle taken in a plane parallel to the axis of the handle but spaced therefrom so that a portion of the handle is shown in elevation. In this view the incendiary bomb is shown within the scoop. The lid is shown in solid lines in closed position and in dotted lines in open position.

Figure 4 is a fragmentary view in perspective of a modified form of control for the cover of the scoop.

Referring to Figs. 1-3 inclusive, the scoop 10 comprises a relatively long handle 11 which may be made of wood or other suitable material and

it may be generally cylindrical in shape. The lower end of the handle 12 cooperates with a socket 13 integral with or fixedly secured to the lower part or main portion of the scoop body 14 as best illustrated in Figure 3. Cooperating with the scoop body part 14 is the curved cover 15 provided with vertical sides 16 which cooperate in overlapping relation with the vertical sides 17 of the scoop body part 14. Secured centrally of the cover 15 is the pierced angle bracket 18 to which is secured in pivotal relation the flexible operating rod 19 the lower end of which comprises a loop extending through the pierced angle bracket 18. The flexible operating rod 19 extends upwardly through the eyelets 20, 21 and 22 to its upper end 23 which is formed in the shape of a finger gripping ring 24. The eyelets 20, 21 and 22 are secured to the upper side of the relatively long handle 11.

20 The cover 15 comprises a top portion 25 of less dimension in the general direction of the axis of the handle than the length of the side 16 extending in the same direction so that the cover 15 may be opened to a relatively great extent as shown in the broken lines in Figure 3 without interference with the socket 13 or the handle 11.

25 The metal body portion 14 and the metal cover 15 are provided on their entire interior surfaces, with the exception of the interior of the sides 16 of the top 15, with a reinforced refractory relatively high heat resisting construction which comprises a layer of expanded metal lath 26 coated with a refractory cement 27 which may include such refractory materials as zirconium sand or calcium oxide or other refractory mediums and a suitable binder therefor so that the refractory medium may be applied in the form of a plaster or cement. The expanded reinforcing metal lath 26 is secured to the interior surfaces 30 of the scoop body portion and cover by spot welding or the like.

30 In order to protect the edges or margins of the refractory medium from abrasion and the like, the margins of the exterior metal portions 28 are turned inwardly at 29 to form an acute angle as best shown in Fig. 3. The rear edge 30 of the cover 15 overlaps the forward edge 31 of the top of the body portion 14 as shown in Fig. 3 when the cover 15 is in closed position.

35 The cover 15 is pivotally connected to the body portion 14 by the pintles 32 which may be rivets or bolts or pins provided with suitable securing means at both inner and outer ends which do not interfere with the pivoting action of the cover.

40 These pintles pass through the sides 16 of the

45

50

55

cover 15 and the sides 17 of the body portion 14.

In Figure 4 a modified form of control for the cover of the scoop is depicted. On the relatively long handle 110 is mounted a pierced guide bracket 102 through which passes the flexible operating rod 119. Secured to the operating rod 119 as by welding is a fixed washer or retaining means 103 against which the compression spring 104 is adapted to bear. At the opposite end the spring 104 bears against the lower side of the fixed bracket 102 so that when the flexible operating rod 119 is drawn upwardly by pulling on the upwardly bent projection 105 against the action of the compression spring 104, the operating rod 119 may be locked in its upper position by lowering the catch lever 106 through the ring 124 formed integral with the operating rod 119. The catch lever 106 is pivotally mounted at 107 on the handle 110 and is provided at its opposite end with a trigger 108 which is normally held in its upper position by the small compression spring 109 which is in a fixed socket. By pressing downwardly on the trigger 108 against the action of the spring 109, the catch lever 106 is forced upwardly and out of the ring 124 so that under the influence of the spring 104 the operating rod 119 moves downwardly until the upwardly extending projection 105 engages the upper face of the bracket 102 during which time the cover 15 will move from fully open position to fully closed position as shown in Fig. 3.

Whether the scoop is provided with operating means as shown in Fig. 1 or as shown in Fig. 4, the method of use of the scoop is substantially the same. The operator who is prepared to immediately seize the scoop from a convenient place upon receiving a signal that an incendiary bomb has been dropped on the user's premises which may be a factory or school, a church or a hospital or some other vulnerable building, takes up the scoop by the handle which may be a relatively long rod of the dimension corresponding to seven feet or more, approaches the incendiary bomb B as shown in Fig. 1, pulls on the ring 24 so that the cover is in open position, scoops up the bomb within the body portion 14 as shown in Figure 3 and then releases the ring 24 so that the cover 15 may snap shut and trap the bomb B. The user may also approach the bomb with the cover in open position so that the forward movement of the scoop taken with the weight of the forward portion of the cover 15 will snap the scoop shut and trap the bomb B as shown in Figure 3. When using a scoop provided with the control shown in Fig. 4, the bomb may be approached with the scoop in open position so that it is only necessary to press the trigger 108 after the bomb B has been scooped up in order to release the cover 15 so that the scoop will be snapped shut by the action of the spring 104.

The scoop is intentionally not made airtight so that the gases emanating from the bomb B may be dissipated without injury to the scoop itself. The high heat resisting lining of the scoop protects the same from damage while the bomb is within the scoop and at the same time protects the user and others who may be about from particles which may fly from the bomb.

After the bomb has been scooped up with the

utilization of the mechanism described, the bomb may be left within the scoop until it is dissipated or it may be transferred to a safe place and then the cover of the scoop may be opened so that the bomb may be deposited in said safe place where no destruction of valuable property or injury to persons may be accomplished by the bomb.

It will be obvious to those skilled in the art that various changes may be made in this device without departing from the spirit of the invention and therefore the invention is not limited to what is shown in the drawing and described in the specification but only as indicated in the appended claims.

15 I claim:

1. A scoop comprising a relatively long handle, a scoop connected to said handle at its lower end, said scoop comprising a body portion and a cover, said body portion having a generally flat bottom wall formed integral at its rear portion with an upwardly extending rear wall having a forwardly turned portion adjacent the top thereof, said cover being pivotally connected to said body portion in such a manner that a portion of said cover overlaps the forwardly extending portion of the top of the rear wall of said body when said cover is in closed position, said body portion and said cover being lined with a heat resisting medium comprising a reinforced refractory layer.

2. The structure recited in claim 1, an operating mechanism for said cover, remote control means for said operating means.

3. The structure recited in claim 1, spring actuated means for controlling the operation of said cover.

4. A scoop comprising a relatively long handle, a scoop connected to said handle, said scoop comprising an outer metal layer, foraminous metal lath reinforcing means secured to said metal layer on the interior thereof and refractory medium coated on said metal lath, said scoop comprising a lower main body portion, a hinged cover therefor, said cover comprising a top portion and two end portions, only the top portion thereof being lined with refractory medium.

5. A scoop comprising a relatively long handle, a scooping mechanism connected to said handle at its lower end, said scoop mechanism comprising a body portion having a relatively flat bottom wall turned upwardly and forwardly at its rear portion to form a pocket, said body portion having generally upstanding sides connecting the sides of said flat bottom portion with the sides of the upwardly and forwardly extending rear of said body portion, said body portion being lined with refractory material, said scoop mechanism also including a cover hinged to the upstanding sides of said body portion, said cover comprising a top which when the cover is in closed position extends from the most forward point of the relatively flat wall of the body portion rearwardly to a point overlapping and above the top of the forwardly extending rear portion of the body, said cover also having sides arranged in overlapping relation to the sides of said body portion, the underside of the top only of the cover being lined with refractory material and the inner sides of the sides of the cover being unlined.

THOGER G. JUNGERSEN.
